UNITED STATES PATENT OFFICE.

EVERETT L. THOMPSON, JR., OF DOVER, NEW JERSEY, ASSIGNOR TO SYPHO-CHEMICAL SPRINKLER CORPORATION, OF CROTON-ON-HUDSON, NEW YORK, A CORPORATION OF NEW YORK.

CHEMICAL FIRE-EXTINGUISHING APPARATUS.

1,206,173.

Specification of Letters Patent. Patented Nov. 28, 1916.

Application filed October 27, 1915. Serial No. 58,096.

To all whom it may concern:

Be it known that I, EVERETT L. THOMPSON, Jr., a citizen of the United States, and resident of Dover, Morris county, New Jersey, have made a certain new and useful Invention Relating to Chemical Fire-Extinguishing Apparatus, of which the following is a specification, taken in connection with the accompanying drawing, which forms 10 part of the same.

This invention relates especially to chemical fire extinguishing apparatus in which a supplemental supply of extinguishing liquid is connected to the distributing system and 15 comprises a chemical mixing tank and co-operating mixing devices which may be operated through a pressure reduction occurring in the distributing system under fire emergency conditions. The mixing devices comprise a suction chamber which may contain a charge of 20 acid or pressure producing chemical that may be discharged into the mixing tank as by an automatically starting siphon in the chamber. A co-operating primary chemical receiver containing a starting charge of liquid 25 which may for instance be similar chemical has its starting siphon or other transferring device arranged to discharge into the suction siphon chamber with which communicates a 30 suction actuating connection with any suitable part of the system, so that on the fire emergency discharge of liquid from the distributing system sufficient suction, that is relative reduction of pressure is created in 35 the suction siphon chamber so as to actuate the starting siphon and simultaneously act upon the automatically discharging siphon and prevent or retard its operation until the starting siphon has finished discharging into 40 the suction chamber a predetermined amount of the primary charge from the receiver. Then the rush of air through the starting siphon may break the suction in the chamber and a predetermined charge of acid or 45 other pressure producing chemical is automatically discharged into the mixing tank, without the necessary action of any rigid moving parts, thus insuring the action of a definite amount of this pressure producing 50 chemical in the mixing tank and securing the development of the desired emergency pressure which is especially desirable where chemical means are used to subsequently

maintain the initial emergency pressure thus developed in the tank. 55

In the accompanying drawings showing in a somewhat diagrammatic way illustrative embodiments of the invention, Figure 1 is a sectional elevation illustrating an embodiment of this invention; and Fig. 2 is a 60 similar view showing another arrangement.

The distributing system may be of any suitable type and construction and may comprise a supply pipe or riser 1 and connected distributing lines 2 supplying any desired 65 distributing devices such as the automatic sprinkler heads 3 arranged at various points around the building to be protected. Any suitable extinguishing liquid 6 may if desired be normally contained in the distributing system and may be supplied thereto under the desired moderate initial head or pressure as by the use of an elevated priming or actuating tank 4, for instance, preferably extending the desired distance above 70 the upper part of the distributing system and provided in some cases with a pin hole or other small vent 5. A supplemental supply of extinguishing liquid is connected to the distributing system in any suitable way 75 and may comprise the chemical mixing tank 8 containing, for instance, a charge of carbonate extinguishing liquid 9, the supply connection or lower extension of the supply pipe 1 in which is located the check valve 37 80 having if desired a suitable differential action, preferably extending into the mixing tank adjacent the bottom thereof and being in some cases provided with a suitable 85 strainer, such as 10, so that when the co-operating chemical mixing devices come into action the desired emergency pressure of 90 50 to 100 pounds or so per square inch is developed through the chemical action taking place in the tank and thus causes the forcible 95 discharge of liquid from the distributing devices in operation.

The chemical mixing devices may, if desired, comprise a suitable casing 21 mounted on the mixing tank and communicating 100 therewith through the opening 18, the casing being normally tightly closed by a suitable cover 11. This casing may contain one or more co-operating charges of sulfuric acid or other pressure producing chemical adapted to react with the liquid in the mixing 105

5 tank and the suction siphon chamber 34 preferably containing a charge 25 of such acid or chemical in its bottom 31 which may be of reduced area to promote complete discharge therefrom, may be mounted in any desired way in the casing and have a closed top which may with advantage in some cases be provided with a pin-hole or other reduced area vent 33.

10 Any suitable discharge device may be arranged in connection with the siphon chamber, such, for instance, as the automatically discharging siphon indicated having a discharge pipe 22, the lower end 19 of which 15 communicates with the mixing tank, the upper end 23 of this pipe being normally somewhat above the level of the charge 25 in the chamber and a siphon bell 20 being, if desired, arranged in connection with this 20 pipe so that the lower inlet end 24 of this siphon bell extends adjacent the reduced area bottom of the chamber so as to largely or substantially discharge the liquid therein when this siphon comes into action.

25 A primary receiver or chamber 28 adapted to contain suitable liquid which if desired may be similar to the charge 25, may be suitably arranged within the casing at any suitable distance above the suction chamber and 30 may contain a starting charge 29 of acid or other chemical, any suitable coöperating transfer device such as the starting siphon 27, which is preferably of large area to quickly effect the discharge of this starting 35 charge, having a delivery end 26 extending if desired, within the suction siphon chamber while its receiving end 30 extends down nearly to the reduced area bottom of the primary receiver so as to withdraw practically 40 all of the charge 29 therefrom. Under fire emergency conditions a suitable suction or pressure reduction is caused by any suitable means in the suction siphon chamber as by connecting therewith the suction actuating 45 pipe or connection 7 which may communicate with any desired part of the distributing system where a suitable pressure reduction or suction impulse is developed on the fire emergency discharge of liquid from the system.

50 Thus under such emergency conditions a corresponding suction or pressure reduction is produced in this suction siphon chamber which actuates the starting siphon so that it begins to deliver the starting charge into 55 the suction siphon chamber. This suction impulse also tends with this illustrative form of the invention to suck material into the chamber through the automatically discharging siphon therin so that the acid or 60 other chemical is drawn down in the annular space within the siphon bell to an extent corresponding with the suction acting in the chamber; and the action of this discharge siphon is thus prevented or retarded 65 so long as the suction is maintained in this

chamber even though the level of the liquid outside the siphon bell 20 might rise somewhat above the upper end 23 of the discharge pipe; and in case an excessive suction occurs in the suction chamber gas can 70 be intermittently drawn into it from the tank without sufficiently breaking the suction within the suction chamber to allow discharge of acid therefrom.

The starting siphon may quickly deliver 75 substantially all the starting charge 29 into the suction siphon chamber, this action being promoted by the normal continuance of the suction within the chamber, and when this starting charge has been withdrawn 80 from its primary receiver 28 so that the liquid level therein is below the bottom 30 of the receiving end of the starting siphon, the siphon will clear itself of liquid if the effective discharge head is made sufficient 85 in relation to the area of its inlet end, and then the air within this receiver quickly passes through the siphon in sufficient quantities to effectively break the suction within the suction siphon chamber 34 by substantially equalizing the pressure within the casing 21 inside and outside of this suction chamber. Thus the acid charge in the chamber which is then above the upper end 23 of the discharge pipe of the automatically 90 discharging siphon quickly flows into this pipe and starts this siphon which continues to discharge this entire charge of acid or other pressure producing chemical into the tank to therein develop the desired emergency pressure through resulting chemical action. This insures the delivery of the desired amount of sulfuric acid or other pressure generating chemical into the mixing tank since the pressure caused in the tank 95 by the chemical action of the first part of this acid cannot stop or substantially interfere with the discharge of acid from the suction siphon chamber, and at the same time the starting siphon can act so quickly 100 that no undesirable delay need occur after the distributing system comes into action in the event of fire before the acid or other pressure producing chemical is discharged 105 into the mixing tank.

110 By properly proportioning the charges of sulfuric acid or other chemical in the primary receiver and suction siphon chamber the desired amount may be discharged 115 into the mixing tank so as to generate the predetermined amount of pressure therein which is best suited for the particular system and distributing devices employed in any installation. If desired additional means may in some cases also be used to insure the breaking of the suction within the 120 suction chamber 34 and for this purpose it is sometimes desirable especially where the effective head on the starting siphon is 125 small at the end of its discharge to employ 130

any suitable suction break which may be in the form of a siphon shaped passage between the suction chamber and the starting receiver and having its inlet end in the receiver located somewhat higher than the inlet end of the starting siphon. If desired, however, this vacuum break which may be in inverted U-tube form may extend sufficiently above the initial level of the starting charge 29 so as not to act as a siphon and Fig. 1 shows such an arrangement in which the suction break 53 has its inlet end 54 arranged within the starting charge but some distance above the inlet end 30 of the starting siphon 27. The lower end 55 of this suction break may as indicated extend within the suction chamber 34 so that when the starting siphon has acted to withdraw the starting charge from the receiver so that its level falls below the inlet end 54 of the suction break passage this device will operate to admit sufficient air to the suction chamber to break the suction or pressure reduction therein after sufficient liquid in the shorter leg of this suction break flows out of the same so that the remaining liquid is thereupon carried up through this communicating passage leaving an open air passage therethrough. The suction is thus broken when a substantially predetermined amount of the starting charge has been transferred to the suction chamber, and the starting siphon under these conditions continues to discharge from the receiver any liquid above the inlet end 30 of this siphon. The emergency pressure initially produced through this chemical action may be subsequently maintained by any desired devices, for example, a supplemental chemical or acid chamber 12 being shown within the casing for this purpose and preferably provided with a pin-hole or small area vent 32 in its top. A charge 16 of sulfuric acid or other pressure producing chemical may be placed in this chamber which may be provided with an automatic pressure maintaining siphon or discharge device which may comprise the discharge pipe 13 communicating with the mixing tank and having its upper end 15 somewhat above the normal level of the charge 16 in this chamber. The siphon bell 14 which may extend around this discharge pipe within the chamber may have its lower receiving end 17 adjacent the reduced area bottom of the chamber so as to discharge substantially all of the acid or chemical therefrom. When the emergency pressure is developed in the mixing tank as previously described this pressure acts through the discharge pipe 13 to force additional air or gas into the supplemental chamber 12 so that the upper part of this chamber which is preferably of relatively large area above the chemical charge therein is under substantially the full emergency pressure. When the continued discharge from the system reduces this emergency pressure in the tank the gaseous pressure in this supplemental chamber forces therefrom a portion of the chemical charge which acts in the mixing tank to bring the pressure therein up to substantially the initial emergency pressure when this discharge automatically ceases until the mixing tank pressure again falls. Thus through such intermittent discharges of acid or other pressure producing chemical from the supplemental chamber the desired emergency pressure can be substantially maintained throughout at least a large part of the discharge of liquid from the tank and system.

As shown in Fig. 2 the distributing system containing any suitable extinguishing liquid may have the top of the supply pipe 1 closed as by a cap 45 and a suitable gaseous pressure actuating tank, such as 46, may be connected to any desired part of the distributing system and contain a sufficient charge of extinguishing liquid at least for priming purposes to supply slight leakage, etc., and also sufficient air or other suitable gas under sufficient pressure to create enough pressure throughout the system to cause discharge of liquid from this priming actuating tank from any opening distributing device. The supplemental supply of extinguishing liquid 8 could in this case be similarly charged with carbonate liquid 9 and a generally similar casing 41 may be mounted in connection therewith and normally closed by the cover 42 so as to contain the chemical mixing devices. These mixing devices may in this instance comprise a similar suction chamber 34 having an automatically discharging siphon 19 to discharge the sulfuric acid or other pressure producing chemical into the mixing tank below. The co-operating primary receiver 37 mounted at any desired distance above the suction chamber may have a starting device or siphon 39 which may as indicated be of the bell type and comprise the siphon bell 56, the lower end 57 of which extends adjacent the bottom of the reduced area sump or bottom portion of the receiver. In order to cause a suction impulse or pressure reduction within the suction chamber 34 the suction actuating pipe or connection 48 may be carried from the air pressure actuating tank 46, for instance, so that on the fire emergency discharge of liquid from the distributing system a sufficient pressure reduction is caused in this tank so that when transmitted through the actuating pipe the pressure in the suction chamber 34 is correspondingly reduced and the resulting relative pressure reduction or suction is sufficient to operate the starting siphon 39 and discharge the pressure producing chemical or other liquid

starting charge from the end 43 of this siphon communicating with the suction chamber. This suction impulse simultaneously prevents the action of the discharge siphon 19 until the predetermined amount of the starting charge has been transferred to the suction chamber, whereupon the suction therein is broken as by the starting siphon clearing itself so as to discharge into the mixing tank the amount of chemical in the suction chamber which is sufficient to flow out over the upper end 22 of the discharge siphon. If desired, however, a suitable siphon suction break passage may be arranged between the suction chamber and a point in the primary receiver which is preferably somewhat above the inlet end of the starting siphon. As indicated this siphon suction break 59 may communicate at its discharge end 58 with the suction chamber and its inlet end 60 may be arranged slightly above the inlet end 57 of the starting siphon, this difference in level being somewhat exaggerated in the drawing for the sake of clearness.

Since the siphon suction break passage is at its upper end at about the same level with the starting siphon the suction impulse caused under emergency conditions in the suction chamber 34 tends to start both the siphon devices in operation so that the suction break may thus facilitate the transfer of the starting charge into the suction chamber below and constitute an additional means for this purpose so as to minimize the danger of failure in case the starting siphon fails to function properly. This relatively small area siphon passage naturally clears itself of liquid by a continuance of its siphon action after the liquid in the primary receiver has fallen below the inlet end 60 of this suction break and thereafter the suction break acts as an air passage freely admitting air to the suction chamber so as to break the suction therein and equalize the pressure in the casing 41 both inside and outside the suction chamber 34. This makes certain the starting of the discharge siphon 19 after a predetermined amount of the starting charge has been transferred to the suction chamber, the starting siphon continuing its action so as to transfer substantially all of the remaining starting charge which is above its inlet end 57 so that a definite amount of pressure producing chemical is thus quickly delivered into the mixing tank 8 to create the desired emergency pressure in the tank and connected distributing system. As indicated a pin hole or small area vent 36 may be provided to vent the suction chamber and may be located in the bell 20 of the discharge siphon if desired. Any desired means may be employed for automatically maintaining this emergency pressure and a supplementary chemical

acid chamber 12 with an automatic pressure maintaining siphon discharge devices 13 similar to what has been previously described is indicated for this purpose.

This invention has been described in connection with a number of illustrative embodiments, forms, proportions, arrangements and numbers of parts, to the details of which disclosure the invention is not of course to be limited, since

What is claimed as new and what is desired to be secured by Letters Patent is set forth in the appended claims:

1. In chemical fire extinguishing apparatus, a vented distributing system normally charged with extinguishing liquid and comprising automatic distributing devices, and a supplemental supply of extinguishing liquid connected to said system and comprising a chemical mixing tank and a co-operating casing containing chemical mixing devices to discharge pressure producing chemical into said mixing tank, including a suction siphon chamber having a reduced area bottom containing a charge of pressure producing chemical, an automatically discharging siphon arranged in said chamber and having a discharge pipe delivering into said mixing tank, a primary chemical receiver containing a starting charge of similar pressure producing chemical, a starting siphon co-operating with said receiver and having its discharge end communicating with said suction siphon chamber to discharge therein, a pneumatic suction actuating connection between the upper part of said distributing system and said suction siphon chamber to create a suction in said chamber on the fire emergency discharge of liquid from said system and thereby actuate said starting siphon and simultaneously retard the action of said automatically discharging siphon until said starting charge has been delivered into said chamber.

2. In chemical fire extinguishing apparatus, a distributing system normally charged with extinguishing liquid and comprising distributing devices, and a supplemental supply of extinguishing liquid connected to said system and comprising a chemical mixing tank and chemical mixing devices to discharge pressure producing chemical into said mixing tank, including a suction siphon chamber having a reduced area bottom containing a charge of pressure producing chemical, an automatically discharging siphon arranged in said chamber and having a discharge pipe delivering into said mixing tank, a primary chemical receiver containing a starting charge of similar pressure producing chemical, a starting siphon co-operating with said receiver and having its discharge end communicating with said suction siphon chamber to discharge therein, a pneumatic suction actuating connection between

- said distributing system and said suction siphon chamber to create a suction in said chamber on the fire emergency discharge of liquid from said system and thereby actuate 5 said starting siphon and simultaneously retard the action of said automatically discharging siphon until said starting charge has been delivered into said chamber, and automatic pressure maintaining means co-operating with said mixing tank to discharge chemical therein.
3. In chemical fire extinguishing apparatus, a distributing system normally charged with extinguishing liquid and comprising distributing devices, and a supplemental supply of extinguishing liquid connected to said system and comprising a chemical mixing tank and a co-operating casing containing chemical mixing devices to discharge pressure producing chemical into said mixing tank, including a suction siphon chamber containing a charge of pressure producing chemical, an automatically discharging siphon arranged in said chamber 20 and having a discharge pipe delivering into said mixing tank, a primary chemical receiver containing a starting charge of similar pressure producing chemical, a starting siphon co-operating with said receiver and having its discharge end communicating with said suction siphon chamber to discharge therein, a pneumatic suction actuating connection between the upper part of said distributing system and said suction 25 siphon chamber to create a suction in said chamber on the fire emergency discharge of liquid from said system and thereby actuate said starting siphon and simultaneously retard the action of said automatically discharging siphon until said starting charge has been delivered into said chamber.
4. In chemical fire extinguishing apparatus, a distributing system comprising automatic distributing devices, and a supplemental supply of extinguishing liquid connected to said system and comprising a chemical mixing tank and co-operating chemical mixing devices to discharge pressure producing chemical into said mixing 30 tank including a suction siphon chamber containing a charge of such chemical, an automatically discharging siphon arranged in said chamber and having a discharge pipe delivering into said mixing tank, a primary chemical receiver containing a starting charge of such chemical, a starting siphon co-operating with said receiver and having its discharge end communicating with said suction siphon chamber to discharge therein, a suction actuating connection between said distributing system and said suction siphon chamber to create a suction in said chamber on the fire emergency discharge of liquid from said system and thereby actuate said starting siphon and simultaneously retard the action of said automatically discharging siphon until said starting charge has been delivered into said chamber.
5. In chemical fire extinguishing apparatus, a distributing system normally charged with extinguishing liquid and comprising distributing devices, and a supplemental supply of extinguishing liquid connected to said system and comprising a chemical mixing tank and co-operating chemical mixing devices to discharge pressure producing chemical into said mixing tank including a suction siphon chamber containing a charge of such chemical, an automatically discharging siphon arranged in said chamber and having a discharge pipe delivering into said mixing tank, a primary chemical receiver containing a starting charge of such chemical, a starting siphon co-operating with said receiver and having its discharge end communicating with said suction siphon chamber to discharge therein, a pneumatic suction actuating connection between said distributing system and said suction siphon chamber to create a suction in said chamber on the fire emergency discharge of liquid from said system and thereby actuate said starting siphon and simultaneously retard the action of said automatically discharging siphon until said starting charge has been delivered into said chamber.
6. In chemical fire extinguishing apparatus, a distributing system comprising distributing devices, and a supplemental supply of extinguishing liquid connected to said system and comprising a chemical mixing tank and co-operating chemical mixing devices to discharge pressure producing chemical into said mixing tank including a suction siphon chamber containing a charge of such chemical, an automatically discharging siphon arranged in said chamber and having a discharge pipe delivering into said mixing tank, a primary chemical receiver containing a starting charge of such chemical, a starting siphon co-operating with said receiver and having its discharge end communicating with said suction siphon chamber to discharge therein, a suction actuating connection between said distributing system and said suction siphon chamber to create a suction in said chamber on the fire emergency discharge of liquid from said system and thereby actuate said starting siphon and simultaneously retard the action of said automatically discharging siphon until said starting charge has been delivered into said chamber.

chamber to thereby discharge a substantially definite amount of such chemical without the use of rigid moving parts and automatic pressure maintaining means coöperating 5 with said mixing tank.

7. In chemical fire extinguishing apparatus, a vented distributing system comprising automatic distributing devices, and a supplemental supply of extinguishing liquid 10 connected to said system and comprising a chemical mixing tank and chemical mixing devices to discharge pressure producing chemical into said mixing tank including a suction siphon chamber containing a charge 15 of acid pressure producing chemical, an automatically discharging siphon device arranged in said chamber and having a discharge pipe delivering into said mixing tank, a primary chemical receiver containing a 20 starting charge of such acid chemical, a large area starting siphon device coöperating with said receiver and having its discharge end communicating with said suction chamber to discharge therein, a pneumatic 25 suction actuating connection connected to said suction chamber to automatically create a suction in said chamber on the fire emergency discharge of liquid from said system and thereby actuate said starting device and 30 simultaneously retard the action of said automatically discharging device until a substantially definite amount of said starting charge has been delivered into said chamber, and automatic pressure maintaining means 35 coöperating with said mixing tank.

8. In chemical fire extinguishing apparatus, a distributing system normally charged with extinguishing liquid and comprising distributing devices, and a supplemental supply of extinguishing liquid connected to said system and comprising a chemical mixing tank and coöperating chemical mixing devices to discharge pressure producing chemical into said mixing 40 tank including a suction chamber containing a charge of such chemical, an automatically discharging siphon device arranged in said chamber and having a discharge pipe delivering into said mixing tank, a primary 45 receiver containing a starting charge of such chemical liquid, a siphon starting device coöperating with said receiver and having its discharge end communicating with said suction chamber to discharge therein, a 50 pneumatic suction actuating connection between the upper part of said distributing system and said suction chamber to create a suction in said chamber on the fire emergency discharge of liquid from said system 55 and thereby actuate said starting device and simultaneously retard the action of said automatically discharging device until said starting charge has been delivered into said chamber to thereby discharge a substantially 60 definite amount of such chemical without the 65

use of rigid moving parts, and automatic pressure maintaining means coöperating with supplemental supply of extinguishing liquid.

9. In chemical fire extinguishing apparatus, a distributing system comprising distributing devices, and a supplemental supply of extinguishing liquid connected to said system and comprising a chemical mixing tank and coöperating chemical mixing devices to discharge pressure producing chemical into said mixing tank including a suction chamber containing a charge of such chemical, an automatically discharging siphon device arranged in said chamber and having a discharge pipe delivering into said mixing tank, a primary receiver containing a starting charge of such chemical liquid, a siphon starting device coöperating with said receiver and having its discharge end communicating with said suction chamber to discharge therein, a pneumatic suction actuating connection between said distributing system and said suction chamber to create a suction in said chamber on the fire emergency discharge of liquid from said system and thereby actuate said starting device and simultaneously retard the action of said automatically discharging device until said starting charge has been delivered into said chamber to thereby discharge a substantially definite amount of such chemical without the use of rigid moving parts, and automatic pressure maintaining means coöperating with supplemental supply of extinguishing liquid.

10. In chemical fire extinguishing apparatus, a distributing system comprising distributing devices, and a supplemental supply of extinguishing liquid connected to said system and comprising a chemical mixing tank and coöperating chemical mixing devices to discharge pressure producing chemical into said mixing tank including a suction chamber containing a charge of such chemical, an automatically discharging siphon device arranged in said chamber and having a discharge pipe delivering into said mixing tank, a primary receiver containing a starting charge of liquid, a starting device coöperating with said receiver and having its discharge end communicating with said suction chamber to discharge therein, a suction actuating connection between said distributing system and said suction chamber to create a suction in said chamber on the fire emergency discharge of liquid from said system and thereby actuate said starting device and simultaneously retard the action of said automatically discharging device until said starting charge has been delivered into said chamber to thereby discharge a substantially definite amount of such chemical without the use of rigid moving parts, and automatic pressure maintain-

ing means coöperating with said supplemental supply of extinguishing liquid.

11. In chemical fire extinguishing apparatus, a distributing system comprising distributing devices, and a supplemental supply of extinguishing liquid connected to said system and comprising a chemical mixing tank and coöperating chemical mixing devices to discharge pressure producing chemical into said mixing tank including a suction chamber containing a charge of such chemical, an automatically discharging device arranged in said chamber and having a discharge pipe delivering into said mixing tank, a primary receiver containing a starting charge of liquid, a starting device coöperating with said receiver and having its discharge end communicating with said suction chamber to discharge therein, a suction actuating connection between said distributing system and said suction chamber to create a suction in said chamber on the fire emergency discharge of liquid from said system and thereby actuate said starting device without the use of rigid moving parts, and automatic pressure maintaining means coöperating with said supplemental supply of extinguishing liquid.

12. In chemical fire extinguishing apparatus, a distributing system comprising distributing devices, and a supplemental supply of extinguishing liquid connected to said system and comprising a chemical mixing tank and chemical mixing devices to discharge pressure producing chemical into said mixing tank including a suction siphon chamber containing a charge of pressure producing chemical, an automatically discharging siphon device arranged in said chamber and delivering into said mixing tank, a primary chemical receiver containing a starting charge of such chemical, a starting siphon device coöperating with said receiver and having its discharge end communicating with said suction chamber to discharge therein, a pneumatic suction actuating connection connected to said suction chamber to automatically create a suction in said chamber on the fire emergency discharge of liquid from said system and thereby actuate said starting device and simultaneously retard the action of said automatically discharging device until a substantially definite amount of said starting charge has been delivered into said chamber, and automatic pressure maintaining means coöperating with said mixing tank.

13. In chemical fire extinguishing apparatus, a distributing system comprising distributing devices, and a supplemental supply of extinguishing liquid connected to said system and comprising a chemical mixing tank and chemical mixing devices to discharge pressure producing chemical into

said mixing tank including a suction siphon chamber containing a charge of pressure producing chemical an automatically discharging device arranged in said chamber and delivering into said mixing tank, a primary chemical receiver containing a starting charge of such chemical, a starting siphon device coöperating with said receiver and having its discharge end communicating with said suction chamber to discharge therein, a pneumatic suction actuating connection connected to said suction chamber to automatically create a suction in said chamber on the fire emergency discharge of liquid from said system and thereby actuate said starting device and simultaneously retard the action of said automatically discharging device until a substantially definite amount of said starting charge has been delivered into said chamber.

14. In chemical fire extinguishing apparatus, a distributing system comprising distributing devices, and a supplemental supply of extinguishing liquid connected to said system and comprising a chemical mixing tank and chemical mixing devices to discharge pressure producing chemical into said mixing tank including a suction chamber containing a charge of pressure producing chemical, an automatically discharging device arranged in said chamber and delivering into said mixing tank, a primary chemical receiver containing a starting charge of such chemical, a starting device coöperating with said receiver and having its discharge end communicating with said suction chamber to discharge therein, a pneumatic suction actuating connection connected to said suction chamber to automatically create a suction in said chamber on the fire emergency discharge of liquid from said system and thereby actuate said starting device and simultaneously retard the action of said automatically discharging device until a substantially definite amount of said starting charge has been delivered into said chamber.

15. In chemical fire extinguishing apparatus, a chemical mixing device adapted to discharge pressure producing chemical into a mixing tank, including a suction siphon chamber having a reduced area bottom containing a charge of such chemical, an automatically discharging siphon device arranged in said chamber and having a discharge pipe delivering into said mixing tank, a primary chemical receiver containing a starting charge of such chemical, a large area starting siphon device coöperating with said receiver and having its discharge end communicating with said chamber to discharge therein, and means adapted to create a suction in said chamber on the fire emergency discharge of liquid from the connected distributing system and thereby actuate said starting device and simultaneously

retard the action of said automatically discharging device until said starting charge has been delivered into said chamber.

16. In chemical fire extinguishing apparatus, a chemical mixing device adapted to discharge pressure producing chemical into a mixing tank, including a suction siphon chamber containing a charge of such chemical, an automatically discharging siphon device arranged in said chamber and delivering into said mixing tank, a primary chemical receiver containing a starting charge of such chemical, a starting siphon device co-operating with said receiver and having its discharge end communicating with said chamber to discharge therein, and means adapted to create a suction in said chamber on the fire emergency discharge of liquid from the connected distributing system and thereby actuate said starting device.

17. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary chemical receiver containing a starting charge of such chemical, a starting siphon device co-operating with said receiver and having its discharge end communicating with said chamber to discharge therein, and means adapted to create a suction in said chamber and thereby actuate said starting device and simultaneously retard the action of said automatically discharging device until said starting charge has been delivered into said chamber.

18. In chemical fire extinguishing apparatus, a chemical mixing device adapted to discharge pressure producing chemical into a mixing tank, including a chamber containing a charge of such chemical, an automatically discharging device arranged in said chamber and delivering into said mixing tank, a primary chemical receiver containing a starting charge of such chemical, a starting device co-operating with said receiver and having its discharge end communicating with said chamber to discharge therein, and means adapted to actuate said starting device and simultaneously retard the action of said automatically discharging device until said starting charge has been delivered into said chamber.

19. In chemical fire extinguishing apparatus, a chemical mixing device adapted to discharge pressure producing chemical into a mixing tank, including a suction siphon chamber containing a charge of such chemical, an automatically discharging siphon de-

vice arranged in said chamber and delivering into said mixing tank, a primary receiver containing a starting charge of liquid, a starting siphon device co-operating with said receiver and having its discharge end communicating with said chamber to discharge therein, and means adapted to create a suction in said chamber on the fire emergency discharge of liquid from the connected distributing system and thereby actuate said starting device.

20. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting siphon device co-operating with said receiver and having its discharge end communicating with said chamber to discharge therein, and means adapted to create a suction in said chamber and thereby actuate said starting device and simultaneously retard the action of said automatically discharging device until a substantially definite amount of said starting charge has been delivered into said chamber.

21. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting device co-operating with said receiver and having its discharge end communicating with said chamber to discharge therein, and means adapted to create a suction in said chamber and thereby actuate said starting device.

22. In chemical fire extinguishing apparatus, a chemical mixing device adapted to discharge pressure producing chemical into a mixing tank, including a chamber containing a charge of such chemical, an automatically discharging device arranged in said chamber and delivering into said mixing tank, a primary receiver containing a starting charge of liquid, a starting device co-operating with said receiver and having its discharge end communicating with said chamber to discharge therein, and means adapted to actuate said starting device.

23. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a

starting charge of liquid, a starting siphon device coöperating with said receiver and having its discharge end communicating with said chamber to discharge therein, and means adapted to create a suction in said chamber and thereby actuate said starting device and simultaneously retard the action of said automatically discharge device until a substantially definite amount of said starting charge has been delivered into said chamber, and automatic pressure maintaining means coöperating with said system.

24. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting device coöperating with said receiver and having its discharge end communicating with said chamber to discharge therein, and means adapted to create a suction in said chamber and thereby actuate said starting device, and automatic pressure maintaining means coöperating with said system.

25. In chemical fire extinguishing apparatus, a chemical mixing device adapted to discharge pressure producing chemical into a mixing tank, including a chamber containing a charge of such chemical, an automatically discharging device arranged in said chamber and delivering into said mixing tank, a primary receiver containing a starting charge of liquid, a starting device coöperating with said receiver and having its discharge end communicating with said chamber to discharge therein, means adapted to actuate said starting device, and automatic pressure maintaining means coöperating with said system.

26. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting siphon device coöperating with said receiver and having its discharge end communicating with said chamber to discharge therein, and means adapted to create a suction in said chamber and thereby actuate said starting device and simultaneously retard the action of said automatically discharge device until a substantially definite amount of said starting charge has been delivered into said chamber, a siphon shaped suction break passage between said suction chamber and a point in said receiver above the inlet end of said starting siphon device, and auto-

matic pressure maintaining means coöperating with said system.

27. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting device coöperating with said receiver and having its discharge end communicating with said chamber to discharge therein, means adapted to create a suction in said chamber and thereby actuate said starting device, a siphon suction break passage between said suction chamber and a point in said receiver above the inlet end of said starting device, and automatic pressure maintaining means coöperating with said system.

28. In chemical fire extinguishing apparatus, a chemical mixing device adapted to discharge pressure producing chemical into a mixing tank, including a suction chamber containing a charge of such chemical, an automatically discharging device arranged in said chamber and delivering into said mixing tank, a primary receiver containing a starting charge of liquid, a starting device coöperating with said receiver and having its discharge end communicating with said chamber to discharge therein, means adapted to create a suction in said chamber and thereby actuate said starting device, a suction break between said suction chamber and said receiver, and automatic pressure maintaining means coöperating with said system.

29. In chemical fire extinguishing apparatus, a chemical mixing device adapted to discharge pressure producing chemical into a mixing tank, including a chamber containing a charge of such chemical, an automatically discharging device arranged in said chamber and delivering into said mixing tank, a primary receiver containing a starting charge of liquid, a starting device coöperating with said receiver and having its discharge end communicating with said chamber to discharge therein, means adapted to actuate said starting device, a siphon suction break passage between said suction chamber and a point in said receiver above the inlet end of said starting device, and automatic pressure maintaining means coöperating with said system.

30. In chemical fire extinguishing apparatus, a chemical mixing device adapted to discharge pressure producing chemical into a mixing tank, including a chamber containing a charge of such chemical, an automatically discharging device arranged in said chamber and delivering into said mix-

- ing tank, a primary receiver containing a starting charge of liquid, a starting device coöperating with said receiver and having its discharge end communicating with said 5 chamber to discharge therein, means adapted to actuate said starting device, a suction break between said suction chamber and said receiver, and automatic pressure maintaining means coöperating with said system.
- 10 31. In chemical fire extinguishing apparatus, a chemical mixing device adapted to discharge pressure producing chemical into a mixing tank, including a suction chamber containing a charge of such chemical, an 15 automatically discharging device arranged in said chamber and delivering into said mixing tank, a primary receiver containing a starting charge of liquid, a starting siphon device coöperating with said receiver and 20 having its discharge end communicating with said chamber to discharge therein and a siphon suction break passage between said suction chamber and a point in said receiver above the inlet end of said starting device.
- 25 32. In chemical fire extinguishing apparatus, a chemical mixing device adapted to discharge pressure producing chemical into a mixing tank, including a suction chamber containing a charge of such chemical, an automatically discharging device arranged in 30 said chamber and delivering into said mixing tank, a primary receiver containing a starting charge of liquid, a starting siphon device coöperating with said receiver and 35 having its discharge end communicating with said chamber to discharge therein, a suction break between said suction chamber and said receiver, and means adapted to create a suction in said chamber and thereby actuate 40 said starting device and simultaneously retard the action of said automatically discharging device until a substantially definite amount of said starting charge has been delivered into said chamber.
33. In chemical fire extinguishing apparatus, 45 a chemical mixing device adapted to discharge pressure producing chemical into a mixing tank, including a chamber containing a charge of such chemical, an automatically discharging device arranged in 50 said chamber and delivering into said mixing tank, a primary chemical receiver containing a starting charge of such chemical, a starting device coöperating with said receiver and having its discharge end communicating with said chamber to discharge 55 therein, a siphon suction break passage between said suction chamber and a point in said receiver above the inlet end of said starting device, and means adapted to actuate said starting device and simultaneously retard the action of said automatically discharging device until a substantially predetermined amount of said starting charge has been delivered into said chamber. 60
34. In chemical fire extinguishing apparatus, 65 a chemical mixing device adapted to discharge pressure producing chemical into a mixing tank, including a chamber containing a charge of such chemical, an automatically discharging device arranged in 70 said chamber and delivering into said mixing tank, a primary chemical receiver containing a starting charge, a starting device coöperating with said receiver and having 75 its discharge end communicating with said chamber to discharge therein, a suction break between said suction chamber and said receiver, and means adapted to actuate said starting device and simultaneously retard 80 the action of said automatically discharging device until a substantially predetermined amount of said starting charge has been delivered into said chamber. 85
